UNITED STATES PATENT OFFICE.

ADOLPH MONTAN, OF WEST ORANGE, NEW JERSEY, ASSIGNOR TO EASTERN TOOL & MANUFACTURING COMPANY, OF BLOOMFIELD, NEW JERSEY.

SLIDE FOR GARMENTS.

Application filed October 16, 1922. Serial No. 594,766.

To all whom it may concern:

Be it known that I, ADOLPH MONTAN, a citizen of the United States, and a resident of West Orange, county of Essex, and State of 5 New Jersey, have invented certain new and useful Improvements in Slides for Garments, of which the following is a specification.

This invention relates to an improved 10 slide for garments, and is particularly adapted for holding the shoulder straps of overalls and similar garments, the slide being one that can be economically manufactured, one that is of simple construction and 15 which has advantages in rigidity and in the flat holding of the straps over prior forms of slide.

The invention is illustrated in the accompanying drawing, in which Figure 1 is 20 a front view of my improved slide. Figure 2 is a top view, and Figure 3 is an end view of the slide.

The slide is formed of wire and is preferably made of square wire, although other 25 forms in cross-section can be employed, this wire being bent to form a rectangular frame comprising the top strand 10, the bottom strand 11 and the end strands 12 and 13. One of the end strands is looped around one 30 of the side strands at one corner of the frame, as at 14, and the side strand so looped then extends as an end strand, shown at 15, and then extends across the frame to form a central strand 16, this central strand 35 at its end being looped around the end strand 13, this loop being shown at 17.

This is a simple and easily manufactured

form of slide, and its rigidity is insured since the loop 17 holds the central strand 16 against any movement away from the main 40 frame, and any movement of the strand 13 is prevented by reason of the off-set portion 18, into which the loop 17 is seated, so that any movement of the loop along this strand 13 is prevented. 45

To hold the strap, threaded through the slide, taut I provide off-set portions 19 which are disposed at right angles to the plane of the slide and are arranged near the ends of said central strand, so that the tendency of the strap, when under tension in the slide, to move toward the center or to one side of the slide is resisted by reason of the protuberances or projections formed by the off-set portions 19. 55

I claim:

A garment slide comprising a wire bent to form a rectangular frame with side strands and end strands, one of the end strands grasping a side strand at one corner of the frame, said side strand extending along the end strand and then across the frame to form a central strand and being looped around the other end strand, said other end strand being slightly off-set where 60 said loop occurs, said central strand having off-set portions at right angles to the plane of the slide and situated only near the ends 65 of said central strand.

In testimony that I claim the foregoing, 70 I have hereto set my hand, this 13th day of October, 1922.

ADOLPH MONTAN.
